UNITED STATES PATENT OFFICE.

THOMAS M. BRINTNALL, OF LOS ANGELES, CALIFORNIA, ASSIGNOR TO THE BRINTNALL MANUFACTURING COMPANY, A CORPORATION OF NEVADA.

COUNTERWEIGHTED LOWERING FLOOR.

Application filed October 29, 1924. Serial No. 746,583.

To all whom it may concern:

Be it known that I, THOMAS M. BRINTNALL, a citizen of the United States, and a resident of Los Angeles, in the county of Los Angeles and State of California, have invented new and useful Improvements in Counterweighted Lowering Floors, of which the following is a specification.

The present invention relates to lowering floors, such as are used in front of bank vaults and the like.

The principal object of my invention is to provide for easy and smooth operation so that a floor may be readily and noiselessly raised or lowered without appreciable physical effort on the part of the operator.

Another object of the invention is to provide mechanism for operating floors of the character described, whereby the action is practically automatic, and does not require power means or means for storing up energy.

Another object of the invention is to provide a construction for such floors, whereby an entire unit may be built, assembled, and tested before being placed in the pit which it is to occupy, and whereby the assembly may be installed in or removed from a pit as a unit.

Another object of the invention is to provide a simple and accurate means for adjusting the mechanism in order that the point of most efficient operation may be reached immediately the assembly is installed.

Another object of the invention is to provide simple and efficient locking means for holding the floor in elevated position so that it cannot descend prematurely or accidentally.

Still other objects and advantages will appear hereinafter and will be better understood by virtue of the order of their occurrence.

I have illustrated by the accompanying drawings a practical embodiment of my invention.

In the said drawings;

Figure 1, is a view in section, mainly on a line 1—1 of Fig. 5 of the said embodiment, showing the principal part of the operating mechanism in plan.

Figure 2, is a view in side elevation of the completely assembled device as it would appear before being placed in its pit, or as it

would appear as seen from along line 2—2 of Fig. 1.

Figure 3, is a plan view of the complete embodiment as it appears in front of a vault door.

Figure 4, is an enlarged detail showing a construction for a fastening means for securing a floor plate, and a covering for same, relative to the complete assembly.

Figure 5, is a view in section seen on a line 5—5 of Fig. 1, looking in the direction indicated by the arrows.

Figure 6, is a fragmentary view in vertical section substantially on the same line on which Fig. 2 is taken, but showing only the coacting parts which form the so called locking mechanism.

Figure 7, is a fragmentary view in vertical section similar to Fig. 6, but showing only the details of certain coacting parts which will be specifically designated and described hereinafter.

Figure 8, is a view in vertical section of one corner of a modified form of floor, showing the details of a part hereinafter known as the auxiliary guiding means.

Figure 9, is a view in section seen on a line 9—9 of Fig. 8.

Figure 10, is a fragmentary view in vertical section of the modified construction for the parts shown in Fig. 7.

In the embodiment illustrated there is provided a large floor plate 12, carried by a rectangular frame 13, of angle iron construction. The frame is reinforced by intermediate cross members or angle iron 14, to which are secured, as at 15, perpendicular angle irons 16. The latter in the embodiment shown are four in number and provide rigidly depending members to which are attached lower transverse irons 18. It will be seen that irons 18 are fixed and spaced below the floor plate an appreciable distance, and all the parts above enumerated will ascend or descend as a unit, and in fact comprise a complete and permanent assembly.

In installing the device, a pit 20 is of course provided, and said pit is provided with a metal lining, such as 21, which is known as the pit casing. Said casing is of open rectangular arrangement, and is held at the top of the pit by means of legs, such as 22 and 23. Said legs and pit casing are

- incorporated in a single removable unit which also includes a rectangular frame 25. Said frame is made up of a rectangular arrangement of channel members 25', 25" etc.
- 5 Said channels are disposed below the pit casing and substantially intermediate of the ends of the legs. Frame 25, legs 22 and 23, and the pit casing 21, may be assembled as a unit before being set in the pit.
- 10 In installing the complete device the said unit is first placed in the pit, together with attached mechanisms about to be described, and subsequently the floor and the floor frame are set in normal position above frame 25.
- 15 25. The bottom cross members 18, of the floor assembly, are arranged to extend outwardly at each end, as at 27, under the longitudinal channel members of frame 25. Therefore in installing the unit, said cross members 18, are attached to the depending members 16, only after the floor is positioned. The extended ends of members 18 are fitted, each with a bolt and jam nut, 27' and 28, respectively; the end of the bolt being arranged to abut the transverse frame member so that the uppermost position of the floor is predetermined.
- 20 A counter weight is provided for the floor in the form of a tray 30, adapted to carry miscellaneous objects 31, so that its weight may be added to as desired to bring the net counter weight effect to the desired point. The floor plate is generally surfaced by a suitable floor composition 32, such as cork, 35 which is held to the floor plates at suitable points by short studs 33. Studs 33 are each provided with a bore 34, whereby a screw 35 may be employed to hold the floor plate and composition assembly to the frame members.
- 40 In other words, the floor plate and composition are first secured to each other by the studs. The screws may then be employed to hold the entire covering to the angle iron frame members. When the entire 45 floating unit of floor, floor covering and frame are assembled, objects may be added to the contents of the counter-weight tray until the total weight is that of the floating floor assembly.
- 50 The counter-weight is operatively and directly connected with the floor through a plurality of cables 40, running over grooved pulleys 41. Each cable is frictionally engaged with the pulley by means of a clamp 55 42, so that the cable cannot slip relative to the pulley. The diameter of the pulleys is such that they do not turn as much as one half of a revolution at any time. The pulleys are arranged in pairs on shaft 43; one 60 pulley at each end of a shaft. Each shaft is held in bearings 44 and 45, respectively, which are secured at 46 to the top surface of the corresponding frame member 25'. Although not shown in the drawing, minimum 65 friction bearings should be employed to

provide for easy movement of the pulleys. Obviously, with correct bearings, careful balance and accurate counter-weight, the floor may be raised and lowered without appreciable effort.

The floor may be moved into lowermost position merely by placing one foot thereon and riding it down. In fact, with careful counter-balancing, a very slight weight added on the floor will move it to such position. The pulleys are fixed to the shafts, as by set screws 47, and to move the floor to raised position, it is only necessary to impart a partial revolution to the shafts jointly. This is done through the medium of crank arms 48, 49 and 50, respectively, and links 51, 52 and 53, together with a bell crank 54. Crank arm 48 is fixed to one of the shafts, while the crank arm 50 is connected to the other shaft. The link is connected to respective cranks by crank pins, such as 55. Therefore, the shafts will always operate in synchronism. The link 52 is connected to the bell crank 54, as at 56, and the link 53 connects the bell crank to a vertically movable push rod 57. The pit casing is supplemented by a lever casing 61, which is disposed around three sides of the space 61'; said space is actually an extension of the pit and contains the above mentioned links. In alignment with the lever casing there is provided a small box-like casing 58 for the bell crank 54 and for the other parts about to be described. A fixed transverse shaft 62 is provided in casing 58, on which shaft the bell crank oscillates. It will be apparent now that when the floor descends, the push rod 57 will ascend. To raise the floor, the push rod 57 is moved downwardly to effect the ascension of the floor.

The operation of raising and lowering the floor is practically apparent from the foregoing and I will now describe the means by which the floor is locked in uppermost position, so that it may uphold any normal weight imposed upon it. Referring particularly to Figs. 5 and 6, it will be seen that the floor assembly carries transverse members 63, which project at each end, as at 64, beyond the vertical members. Said ends are arranged, when the floor descends, to come into abutment with the perimeters 65 of cams, such as 66. The cams are fixed by set screws 67, to shafts 68. In the embodiment shown, there are two shafts; one for each two cams, the cams being four in number. By means of a link, such as 69, and pivot pins 70, one cam on one shaft is connected directly with a corresponding cam on another shaft, so that the cams and shafts will rock in synchronism.

For the purpose of rocking the cams when required, there is provided a push rod 71. Said rod, by means of a pivot pin 72' is connected to a link 73'. Said link, by an-

other pivot pin 72, is connected pivotally with a bell crank 73, pins, such as 74, and a link 75, by means of which it connects with a crank arm 76. Said crank arm is keyed, as at 77, to one 5 of the rock shafts, whereby depression of push rod 71, rocks the shafts and moves the cams to the dotted line position shown in Fig. 6. When the cams are moved out from under the abutting transverse members, the floor is 10 free to be ridden down to lowermost position. The crank arm 76 is weighted, as at 78, and it yieldably tends to return the cams to vertical position. Therefore, when the floor is raised to uppermost position, the 15 weight moves the cams into operative position and automatically locks the floor in the uppermost position. Stops 80 are provided to limit forward movement of the cams.

The door jamb of the vault is indicated 20 by the numeral 81. In installing my automatic floor, the pit, including the lever pit, is extended over to the jamb and is of such length that the door 82 is always in the pit, whether in partial or full open position. A 25 small fixed floor 84 is provided under the open door. The usual bridge 85 is provided leading from the floor to the vault floor 86. The construction, arrangement and purposes 30 of the bridge, and the fixed floor 84 are known to those skilled in the art and is fully set forth in my co-pending application, Serial No. 743,030 filed Oct. 11, 1924. The floor is narrowed at the end remote from the bridge 85, in order to clear the said 35 stationary floor 84.

The operation of the complete embodiment is quite apparent from the foregoing description of the operation of the several parts and assemblies just described. Referring to Fig. 3, the operation may be 40 further explained as follows:—To close the vault door, the bridge is first moved back into the vault. The bridge may be hinged, as at 90, to the floor, so that it may be readily moved out of the way of the closing door. The operator may stand at any convenient 45 point, such as at the point indicated at 91. He places a foot on the push rod and depresses it slightly to release the cams and 50 allow the floor to move downwardly. He places the other foot upon the floor and rides it down to lowermost position. In such lower position the floor will not interfere with the closing of the door. The operator 55 then may walk across the lowered floor to the door and swing it around to the closed position. With the door closed, he places a foot on the other push rod and presses 60 lightly thereon. Depression of said push rod acts through the pulleys and attached shafts to raise the floor to the uppermost position, as described. Now the floor is level 65 with the ante-chamber floor 92 and no open pit is extant.

When it is desired to open the vault door,

the floor is first lowered in the manner just described, the door is opened and the floor is again raised, whereupon the bridge is placed in position. It will be apparent now that the floor may be raised and lowered 70 without the aid of outside power, without stored energy and without the use of the operator's hands. In fact, by treading first on one push rod, then on the floor, and subsequently on the other push rod, he puts 75 the lowering floor through its complete cycle of movements almost without thought or effort on his part, and co-incident with the usual task of opening and closing the vault door. 80

In the form of the invention shown in Figs. 7 to 10, inclusive, the pulleys and cables above described are dispensed with, and instead the counter-weight pan is connected with the floor by a balance arm 95. Said arm is trunnioned at 96 in a bearing 97, supported by member 25'. A link 97 is connected at 97' to the depending member of the floor, while the other end of the link is connected, as at 98 to the corresponding end 90 of the balance arm. A link 99 is pivoted, as at 99' to the counter-weight tray, while the other end of the link is connected, as at 101 to the balance arm. The parts just described are merely a substitute for the pulleys and cables and do not alter the operation of the floor. However, the pulleys and cables keep the floor in correct position in the pit and do not produce side thrust. In the embodiment being described, slight side 95 thrust is produced. Therefore, rollers or casters 102 are attached to the floor plate, as at 103. The rollers may ride in vertical channels 104, to guide the floor vertically. 100

While I have shown and described a 105 specific embodiment of my invention and a modified construction for a part thereof, I do not limit myself to any specific construction or arrangement of parts, and may alter the construction and arrangement of parts as 110 I desire or as occasion requires, without enlarging the scope of my invention, within the appended claims.

I claim—

1. In combination with a vault having a 115 door, a pit in front of said vault and door, through a part of which said door moves to be opened or closed, a floor arranged to move vertically in said pit, a counter-weight for said floor, means operable from a point immediately adjacent said pit for imparting upward movement to said floor, rigid means arranged to automatically move under said floor as it reaches uppermost position; said means adapted to uphold any normal weight 120 subsequently imposed on said floor, and means operable to release said rigid means from engagement with said floor. 125

2. In a device of the class described, upright leg members, a pit casing supported 130

- thereby adjacent the upper ends of said leg members, longitudinal frame members intermediate of the upper and lower ends of said leg members, transverse rock shafts supported by said longitudinal members, a floor movable vertically in the space encompassed by said casing and legs and above said longitudinal members, a counter-weight below said floor movable vertically in said space and below said longitudinal members, means connecting said counter-weight to said floor through the medium of said rock shaft whereby rocking thereof in one direction will raise said floor and lower said weight.
3. In a device of the class described, upright leg members, a pit casing supported thereby adjacent the upper ends of said leg members, longitudinal frame members intermediate of the upper and lower ends of said leg members, transverse rock shafts supported by said longitudinal members, a floor movable vertically in the space encompassed by said casing and legs and above said longitudinal members, a counter-weight below said floor movable vertically in said space and below said longitudinal members, means connecting said counter-weight to said floor through the medium of a rock shaft whereby rocking thereof in one direction will raise said floor and lower said weight, other rock shafts supported by said longitudinal frame members, and rigid means fixed to said other rock shafts whereby one stroke of said other rock shafts will bring said rigid means under said floor to prevent descent thereof, and means operable from above and immediately adjacent said floor for holding said rigid means temporarily out of floor supporting position.
4. In a device of the class described, upright leg members, a pit casing supported thereby adjacent the upper ends of said leg members, longitudinal frame members intermediate of the upper and lower ends of said leg members, transverse rock shafts supported by said longitudinal members, a floor movable vertically in the space encompassed by said casing and legs and above said longitudinal members, a counter-weight below said floor movable vertically in said space and below said longitudinal members, means connecting said counter-weight to said floor through the medium of a rock shaft whereby rocking thereof in one direction will raise said floor and lower said weight, and means for imparting a rocking stroke to said shafts.

4. In a device of the class described, upright leg members, a pit casing supported thereby adjacent the upper ends of said leg members, longitudinal frame members intermediate of the upper and lower ends of said leg members, transverse rock shafts supported by said longitudinal members, a floor movable vertically in the space encompassed by said casing and legs and above said longitudinal members, a counter-weight below said floor movable vertically in said space and below said longitudinal members, means connecting said counter-weight to said floor through the medium of a rock shaft whereby rocking thereof in one direction will raise said floor and lower said weight, other rock shafts supported by said longitudinal frame members, and rigid means fixed to said other rock shafts whereby one stroke of said other rock shafts will bring said rigid means under said floor to prevent descent thereof, and means operable from above and immediately adjacent said floor for holding said rigid means temporarily out of floor supporting position.

THOMAS M. BRINTNALL.
